APPARATUS FOR PREPARATION OF
CELLULATED SLAG

Fred Osborne, Birmingham, Ala., assignor to S. P. Kinney Engineers, Inc., Carnegie, Pa., a corporation of Pennsylvania

Application December 28, 1954, Serial No. 478,137

4 Claims. (Cl. 239—273)

This invention is directed in general to apparatus for cellulating molten slag and more specifically to apparatus of this type which may be readily adjusted to compensate for variations in the volume and viscosity of the molten slag and for varying the size and degree of cellulation of the small masses into which the slag is broken for cellulation.

In my copending application Serial No. 255,029, filed November 6, 1951, now Patent No. 2,702,407, there is disclosed and claimed method and apparatus for progressive cellulation of molten slag by first interrupting a stream of free falling slag by means of a gaseous medium such as steam or air so as to project the slag outwardly as relatively small molten or very hot discrete masses which are subsequently exposed to an atomized water spray to progressively cellulate the slag and produce a product which is very strong and has a density of about $\frac{1}{4}$ of that of the molten slag.

The apparatus disclosed in my copending application is so mounted that once it is placed in operation it will continue to produce uniform quality of cellulated slag provided the free falling stream of slag upon which it operates remained substantially uniform in quantity and quality. Some provision was made for varying the force of the cellulating streams of steam and water, but in the event that it was found desirable to vary the degree of cellulation of the discrete slag masses or to make major adjustments to compensate for variations in the quality or quantity of the free falling slag body it was necessary to shut down the apparatus in order to make the necessary adjustments.

In the present application the apparatus for performing the cellulating operation is substantially that shown in the earlier filed application, however, the method of mounting the air, steam and water nozzles has been materially improved. In the present invention I have provided for both vertical and horizontal adjustment of both the steam and water nozzles and have also provided for independent adjustment of the steam nozzle relative to the water nozzles. Provisions have also been made to vary the size of the masses into which the falling slag is broken by providing for adjustability of both the size and speed of the vapor stream used to break up the molten slag. Each of the foregoing adjustments can be made quickly and readily without shutting down the apparatus.

In the drawings forming part of this disclosure, Fig. 1 shows in side elevation the apparatus in its relation to the slag stream;

Fig. 2 shows a front elevation of the apparatus; and Fig. 3 is an enlarged cross section through the vapor nozzle used to break up the slag stream into discrete masses for cellulation.

Referring now in detail to the drawings, reference character 1 refers to a slag trough which may be constructed of metal having ceramic insulating lining 2 for conveying molten slag from the furnace to a generally semi-cylindrical member 3 having a pour outlet 4 over which the slag moves and flows as a free falling stream

2

into a cellulating chamber 5 where it is broken up and acted upon by the cellulating apparatus. The member 3 is preferably a hollow metallic member which is cooled by water flowing through the inlet 6 and outlet 7 thereof. 5 Suitable conduits being connected with such inlet and outlet for conveying water to and away from the member. The cellulating chamber 5 is also preferably made of metal and is hollow so that water continually flowing therethrough cools the member and prevents rapid deterioration from the heat of the molten slag being operated upon. The member 5 is also semi-cylindrical in shape and extends outwardly from the plane of the falling slag so as to confine the molten discrete masses into which the slag stream is broken for better exposure to the atomized water spray used as a cellulating medium.

Disposed wholly behind the plane of the falling molten slag stream is a vapor nozzle 8 and water atomizing nozzles 9, 10, 11, 12, 13 and 14. Each of the nozzles 9 to 14 inclusive is mounted upon a suitable nipple 15 which is connected by means of a standard flexible ball pipe joint 16 with suitable lengths of pipe 17a, b, c, d, e and f extending therefrom and mounted in a base 18. The pipe sections 17a, b, c, d, e and f extend through the base 18 and terminate in suitable connections 17g for attachment to flexible conduits (not shown) carrying water to the nozzles. As shown in Fig. 2 of the drawings, the nozzles 9 to 13 inclusive are mounted about the inner periphery of the chamber 5 for projecting atomized water into the cellulating chamber. As shown in Fig. 1 of the drawings, the nozzles 9 to 14 are preferably adjusted so that their streams converge adjacent the outer end portion of the member 5. In order to atomize the water flowing through the nozzles 9 to 14 inclusive a suitable air line 56 is connected with each nozzle. The nozzle 14 is similar in all respects to the nozzles 9 to 13 inclusive, but is preferably mounted above the steam nozzle 8 and behind the slag stream for a purpose hereinafter set forth.

The steam nozzle 8 is also mounted on the base 18 by 40 means of a bracket comprising a base portion 19 and spaced side walls 20 reinforced by the ribs 21. The side walls 20 at their upper ends having inwardly turned flanges 22 for guiding engagement with the vapor nozzle 8. As shown in Fig. 3, the vapor nozzle 8 comprises a 45 tapering hollow barrel portion 23 having at one end a discharge opening 24 and at its opposite end an enlarged portion 25 forming a mixing chamber. The chamber 25 terminates in an end wall 26 having a threaded outer periphery upon which is mounted the cap 27. The discharge opening 24 of the portion 23 is substantially rectangular in shape, as shown in Fig. 2 of the drawings, and within the portion 23 adjacent the discharge opening 24 is slidably mounted a member 28 for varying the shape of the discharge opening 24 and velocity of the 50 vapor stream projected from the nozzle. A relatively narrow rib 29 is disclosed above the member 28 and within the portion 23 and spaced to provide clearance for the top of the member 28. Extending into the nozzle 8 through the cap 27 is an operating rod 30 which connects with the member 28 within the nozzle portion 23. 55 A hollow cylindrical guard portion 31 is mounted on the end cap 27 about rod 30 and a removable pin 32 extends through the guard portion 31 for selective engagement with a plurality of adjustment holes 33 disposed along the length of the rod 30 so that the element 28 can be adjustably located relative to nozzle discharge opening 24. Preferably a chain member 34 is connected with the pin member 32 and the cap 27. The degree of adjustment of the member 28 may be any desired amount, a maximum movement to the right and left of $2\frac{1}{2}$ inches from that shown in Fig. 3 of the drawings has been found suitable. The member 28 is shown in fully retracted posi-

tion by dot and dash lines on Fig. 3. A steam connection 35 extends into the chamber 25 and a suitable inlet 36 is also provided for water. On the base portion of the chamber 25 of the nozzle 8, as shown in Fig. 2, are depending legs 37 terminating in flanges 38 for engagement with the flanges 22 of the support bracket 20. On substantially the longitudinal center line is a pad 39 upon which is mounted a section of a rack 40 by means of fastening members 41. The nozzle 8 is movably mounted relative to the bracket side walls 20 by means of a gear 42 mounted on shaft 43 journaled in the side walls 20. An operating handle 44 is mounted on shaft 43 for rotation of the gear 42 providing horizontal movement of the nozzle 8 relative to the bracket 20 and the stream of molten slag issuing from the outlet 4 of member 3.

The assembly of nozzles 8 to 14 inclusive is directly connected with the base member 18 which in turn is connected by vertically adjustable members 45 with a base member 46 which in turn is movably mounted upon the bracket angles 47. The members 47 form part of a suitable bracket 48 attached to the wall 49 upon which the chamber 5 is mounted. Mounted beneath the base member 46 are suitable rack segments 50 engaged by gears 51 mounted upon a shaft 52 journaled on the members 47 by means of the bearings 53 and 53a. One end of the shaft 52 extends beyond the bearing 53a and has an operating handle 54 rigidly mounted on such extension. Upon rotation of the handle 54 and shaft 52 the gears 51 move the base member 46 horizontally upon the members 47 to advance and retract the nozzle assembly towards and away from the chamber 5. As shown in Fig. 1 of the drawings, the members 45 connecting the base member 46 and base 18 are vertically adjustable so that the base 18 and nozzle assembly may be adjusted vertically relative to the supporting base member 46. In order to avoid lateral displacement of the base member 46 on the members 47, guide angles 55 are secured to the base 46 and bear beneath the horizontal leg of the members 47.

When the foregoing apparatus is in operation, the nozzle 8 projects a stream of steam, air or other suitable gaseous medium against the back of the falling molten slag stream. The force and shape of the stream is such as to cause the molten slag to break into small discrete masses which are projected through the chamber 5 by the force of the steam. The nozzles 9 to 13 are simultaneously projecting an atomized water spray, the spray from said nozzles converging outwardly of the plane of the falling slag stream and adjacent the outer end of the chamber 5. The hot discrete masses moving through the atomized water spray are progressively cellulated as set forth in my copending application. As also set forth in the said copending application, nozzle 14 may be utilized to spray atomized water against the slag stream before the stream is broken into discrete masses. The purpose of spray from nozzle 14 is to apply the water in those cases where a particularly viscous slag is being operated upon. Water from nozzle 14 causes some slight cellulation and cooling of the particularly viscous slag making it more amenable to action nozzle 8.

The assembly of nozzles 8 to 14 inclusive may be raised or lowered vertically by manipulation of the members 45 beneath base 18. These members are shown as turnbuckles and rotation in one direction raises base 18, while rotation in the opposite direction lowers base 18 relative to support 46. Nozzle 8 may be adjusted in a horizontal plane relative to the falling slag stream by rotation of handle 44. Rotation of handle 44 in one direction rotates gear 42 in engagement with rack 40 to advance nozzle 8 towards the falling slag stream and chamber 5. Rotation of handle 44 in the opposite di-

rection retracts nozzle 8 from chamber 5. In those cases where it is desired to advance or retract the entire assembly of nozzles 8 to 14 relative to chamber 5, handle 54 may be manipulated to move support 46 by means of gears 51 and racks 50.

For purposes of illustration, rack and pinion operation of the apparatus has been shown and described. A worm and gear type of operation may be substituted for the rack and gear if desired. The use of a worm gear has the advantage of precision of adjustment and lack of back lash. The substitution of the worm gear for the spur gear, and modification of the rack to utilize a worm gear are within the skill of any mechanic. It is for these reasons that additional showing of a worm gear is deemed unnecessary.

This application is a continuation-in-part of my copending application Serial No. 255,029, filed November 6, 1951, now Patent 2,702,407.

I claim:

1. Apparatus for adjustably supporting a group of one form of nozzles and a second form of nozzles relative to each other and to a surface to be acted upon by fluid from said nozzles, comprising a base member mounting a group of first form of nozzles in fixed relation to the base, a bracket supported by the base member and extending upwardly therefrom, a second form of nozzle disposed above said base adjacent said bracket, means on said bracket supporting said second form of nozzle for movement relative to said bracket, a fixed support disposed beneath said base member, a second base member mounted on said support in spaced relation to the first said base member for movement longitudinally of said support, means connecting said spaced base members, and means connecting said second base member and with said support for selectively moving said second base member longitudinally of said support.

2. Apparatus as defined in claim 1 wherein the means for connecting the base members are vertically adjustable.

3. Apparatus as defined in claim 2 wherein the means providing movement of the second form of nozzle relative to the base comprises depending members on the latter nozzle slidably engaging the bracket, a rack member mounted beneath said nozzle and a gear rotatably mounted on the said bracket in engagement with said rack for movement of the rack upon rotation of the gear.

4. Apparatus as defined in claim 3 wherein the means engaging said second base member for movement relative to said fixed bracket comprises, a shaft journaled in said fixed bracket, a gear mounted on said shaft in fixed relation thereto and a rack mounted beneath said base member in engagement with said gear for advancement and retraction of the said second base member upon rotation of said shaft in opposite direction.
